HANDLE FOR A MIRROR OR LIKE ARTICLE

Max H. Storch, Belle Harbor, N. Y.

Application January 11, 1949, Serial No. 177

Term of patent 7 years

(Cl. D86—10)

To all whom it may concern:

Be it known that I, Max H. Storch, a citizen of the United States of America, residing in Belle Harbor, county of Queens, and State of New York, have invented a new, original, and ornamental Design for a Handle for a Mirror or Like Article, of which the following is a specification, reference being had to the accompanying drawing, forming part thereof.

I claim:

The ornamental design for a handle for a mirror or like article, substantially as shown.

MAX H. STORCH.
